UNITED STATES PATENT OFFICE

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA

CAR COUPLER

Application filed October 23, 1929. Serial No. 401,855.

This invention relates to automatic car couplers of the type involving a coupler head, a knuckle pivotally mounted upon the head, and a lock for normally restraining the outward or uncoupling rotation of the knuckle. In addition to these essential features it is desirable to provide couplers of this type with means for automatically rotating the knuckle to open position to put the coupler in readiness for a coupling operation and to provide means for supporting the lock in unlocked position so as to permit the knuckle to rotate outwardly when the car upon which the coupler is mounted is separated from an adjacent car to which it has been coupled. It is also desirable to provide means for preventing the coupler lock from accidentally jarring to unlocked position when in service.

The object of this invention is to provide a car coupler mechanism consisting of a few simple and sturdy parts in which efficient and reliable means are provided for locking the knuckle in coupled position, for preventing the lock from accidentally moving to unlocked position, for maintaining the lock in an unlocked position so as to permit a subsequent uncoupling rotation of the knuckle, and for automatically rotating the knuckle to open position when the lock of the coupler is caused to perform an extended unlocking movement, the organized mechanism being well adapted for permitting the coupler lock to be actuated by an uncoupling device of the side operating lever style.

The principal feature of the invention consists in so constructing and organizing the parts of the car coupler that the lock for the knuckle is readily adapted for actuation by a side operating bell-crank lever pivoted to the coupler head, the coupler head being so formed and the knuckle opener lever being related thereto and to the lock in such manner as to compel the lock to drop to locked position whenever it should do so, thus insuring perfect operation of the lock notwithstanding the provision on the coupler head of a lockset ledge to cooperate with the lock for temporarily retaining the latter in an unlocked position permitting the knuckle to perform an uncoupling rotation.

There are other features of invention residing in the particular construction of parts and in advantageous combinations of elements, all as will hereinafter appear.

In the drawings illustrating a preferred form of the invention, the scope whereof is pointed out in the claims,—

Figure 1 is a plan view of a car coupler embodying the invention, the parts being in coupled relation and a portion of the upper wall of the coupler head being removed to disclose adjacent parts of the lock, knuckle tail and knuckle opener lever.

Figure 2 is a horizontal sectional view of the coupler, the knuckle being in plan and the parts being in the positions they assume after the knuckle has been thrown to fully opened position by the knuckle opener.

Figure 3 is a front elevational view of the coupler, a portion of the outer end of the knuckle being broken away and the parts being in locked relation.

Figure 4 is a detailed sectional view through the guard arm and a portion of the locking pin chamber of the coupler head, showing the locking pin in lockset position.

Figure 5 is a view corresponding to Figure 4 but showing the locking pin in the higher position it assumes just before imparting to the knuckle opener lever a rotary movement to force the knuckle open.

Figure 6 is a vertical longitudinal section of the coupler showing the parts in locked position, the knuckle, lock and knuckle opener being in elevation.

Figure 7 is a detail side elevation of the locking pin, looking in the direction of the guard arm side of the coupler head.

Figure 8 is a detail front elevational view of the locking pin.

Figure 9 is a detail plan view of the locking pin.

Figure 10 is a sectional view on the line 10—10, Figure 8.

Pivotedly mounted upon the coupler head 1 by means of a knuckle pin 2 is a knuckle 3 which is normally prevented from executing an uncoupling rotation by means of the locking pin 4. The tail of the knuckle is preferably provided on its inner side with a hook 100

5 which is designed to extend through an opening 6 in the side of the coupler head in the usual manner, thus providing means for preventing the knuckle from being pulled 5 out of the head in the event the knuckle pin 2 should be broken in service. The knuckle 3 is also provided at its inner extremity with an inclined or bevelled face 7 which slopes 10 downwardly away from the lock engaging face or abutment 8 of the knuckle. When the knuckle is rotated from an open to a closed position the incline 7 upon the knuckle cooperates with a corresponding inclined face 9 upon the locking pin 4 to cause said locking pin to be raised to unlocked position so 15 as to permit automatic locking of the coupler. These cooperating inclines 7 and 9 make it unnecessary to provide a knuckle tail of such width at its inner end cross-wise of the coupler as will prevent the locking pin from 20 dropping when the knuckle is in open or in nearly open position, for these inclines provide means for elevating the locking pin to permit the knuckle to pass thereunder and 25 return to coupled position.

The knuckle opener 10 which is actuated by the lock to force the knuckle to open position is in the form of a bell-crank lever and is arranged so that it swings in a plane forming an oblique angle with the longitudinal axis of the coupler. Its long downwardly extending arm 11 normally bears against the rear of the knuckle tail when the knuckle is closed, while its short arm 12 stands vertically over and in spaced relation to a forwardly projecting lug 13 with which the locking pin is provided toward its upper end. The bell-crank knuckle opener has a horizontally extending cylindrical stud or shaft 30 cast integrally therewith which is journalled in a suitably apertured bearing 15 of the coupler head. The knuckle opener may advantageously be retained in place in the assembled coupler by providing the interior of the coupler head with a forwardly projecting horizontal wall or flange 16 having a face 17 which extends parallel with the path of swing of the lower or long arm 11 of the knuckle opener lever. The side 18 of 35 the wall or flange 16 which faces toward the guard arm side of the coupler is formed parallel with the adjacent side of the body of the locking pin 4. As the flange 16 is positioned vertically so as to overlap the locking pin when the latter is in locked position it serves to guide the locking pin as well as to retain the knuckle opener in place. The locking pin 4 for retaining the knuckle in closed 40 position is of the sliding type which moves to locked position under the influence of gravity. It is formed at its upper end with a block or body portion 19 to which is integrally united a depending leg 20 extending downwardly through an opening 21 in the lower wall of the coupler head. The open-

ing 21 is of sufficient length transversely of the coupler to permit the lower end of the lock-leg 20 to swing laterally toward the knuckle side of the coupler head so as to permit the lock-down lug 22 of the locking pin to be shifted from beneath the portion 23 of the coupler head under which it extends when the parts are in normal locked position. 70

The width of the lock-down lug 22 transversely of the coupler is made slightly less than the amount of backlash in the knuckle and as all coupler knuckles are required to have this necessary backlash no special fitting is required for a coupler with this type of lock-down. The lug 22 and the cooperating portion 23 of the coupler head provide a so-called lock-to-the-lock or lock-down for preventing the lock 4 from accidentally jarring upwardly to unlocked position while the coupler is in service. 80

The upper surface of the projection 22 is bevelled as at 24 so as to slope downwardly toward the guard arm side of the coupler and the under surface 25 of the portion 23 of the coupler head is correspondingly bevelled. These two bevelled faces thus serve to shift the lower end of the lock-leg 20 toward the knuckle side of the coupler head at the beginning of the upward or unlocking movement of the locking pin. As it is the chafing of the knuckle against the side of the locking pin body while the cars are being pulled over uneven places in the tracks that is the cause of upward creeping of locking pins toward unlocked position, it will be perceived that the lock-to-the-lock means herein provided for preventing accidental release of the lock will always be effective whenever there is the least pull on the coupler. 90

The under surface 26 of the body portion of the locking pin 4 overhangs the lock-down lug 22 and is bevelled so as to slope downwardly toward the guard arm side of the coupler head. When the lock is in its lowest position this inclined surface 26 rests upon the corresponding inclined surface or seat 27 forming the upper surface of the portion 23 of the head which cooperates with the lock-down lug 22. The cooperation of the inclined faces 26 and 27 tends to cause the lock when it drops, to move laterally toward the guard arm side of the head so as to bring the lock-down lug 22 beneath the portion 23 of the head with which it cooperates. It will also be appreciated that as the gravity axis of the locking pin 4 is spaced away from the lock supporting seat 27 toward the knuckle side of the head, the lower end of the lock leg 20 will swing toward the guard arm side of the head when the lock is supported on said seat 27, thereby shifting lock-down lug 22 beneath the portion 23 of the head. 110

The inclined under surface or shoulder 26 of the body portion 19 of the locking pin is also adapted to be seated upon a corre- 120

spondingly inclined shoulder or lockset seat 28 formed on the interior surface of the coupler head at the guard arm side. The lockset seat 28 is located sufficiently above the seat 27 for the lock to support the body portion 19 of the lock 4 at a proper elevation to permit the tail of the knuckle to swing outwardly to uncoupled position. In addition to being at a higher elevation than the seat 27 on which the lock rests when in closed position, the lockset seat or ledge 28 is spaced or offset laterally toward the guard arm side of the coupler head so as to be out of the path of movement of the body portion 19 of the locking pin when the latter, after having performed an extended unlocking movement, moves downwardly to locked position. As will be readily understood, when the lock operating bell-crank lever 29 which is pivoted on the knuckle side of the coupler head raises the locking pin 4 the body portion 19 of the latter will swing or move laterally toward the guard arm side of the head as soon as the surface or shoulder 26 of the body 25 is elevated to or slightly above the height of the lockset ledge 28 on the interior of the coupler head, such lateral swinging of the body portion 19 being due to the influence of gravity since the gravity axis of the locking pin passes between the guard arm side of the head and the point of contact of the bell-crank lifting lever 29 with the locking pin 4. Above the lockset ledge 28 the coupler is 30 formed with an inclined or bevelled face 30 designed to cooperate with a correspondingly bevelled face 31 at the upper end of the locking pin 4 adjacent the guard arm side of the coupler. As will be apparent from inspection of Figures 4 and 5 of the drawings, these two bevelled surfaces, 30 and 31, constitute means for shifting the upper end or body portion 19 of the locking pin toward the knuckle side of the coupler when the locking pin is elevated above the position it 35 occupies when supported on the lockset ledge 28. As is well shown in Figure 4, clearance is allowed between the bevelled surface 30 on the coupler head and the bevelled face 31 at the upper end of the locking pin body to permit the locking pin body 19 to move into lockset position when the locking pin 4 is raised the required distance for this operation. It will also be noted that the surface 32 of the locking pin chamber immediately 40 above the inclined shoulder 30 of the coupler head is not in vertical alinement with the lockset ledge 28 of the head but is offset or spaced with respect to the latter transversely of the coupler toward the knuckle. As the 45 upper end of the body portion 19 of the locking pin overlaps this surface 32 of the locking pin chamber when the inclined face 31 of the locking pin has passed out of contact with the cooperating bevelled face 30 of the coupler head in the operation of unseat-

ing the locking pin 4 from the supporting lockset ledge 28, the surface 32 provides means for preventing the shoulder 26 of the locking pin from catching on the lockset ledge 28 when the locking pin drops to locked position in the normal operation of the coupler. 70

In addition to the inclined surface 9 for cooperating with the tail of the knuckle during a closing movement of the latter, the under surface of the body portion 19 of the locking pin is provided with a short bevelled face 33 which slopes upward and toward the knuckle side of the coupler from the inclined surface 9. When the locking pin 4 is in lockset position (see Figure 4) the lower portion of the locking pin body where the inclined surfaces 9 and 33 meet stands somewhat below the upper surface of the tail of the knuckle 3. It thus results that when the knuckle rotates outwardly toward open position while the locking pin 4 is supported on the lockset ledge 28, the tail of the knuckle comes in contact with the bevelled face 33 and automatically raises the locking pin until the lowest part of its body portion 19 can ride upon the top surface of the tail of the knuckle. This upward movement of the locking pin raises it from its lockset seat 28. As the knuckle continues its rotation to an open position the locking pin slides down the inclined surface 7 on the tail of the knuckle, drawing the shoulder 26 out of alinement with the lockset seat 28 and allowing the locking pin 4 to drop to its lowest position and rest on its seat 27 of the coupler head when the knuckle has opened fully or substantially so. Upon a subsequent inward rotation or coupling movement of the knuckle 3 the inclined surface 7 on the tail of the latter contacts with the bevelled face 9 of the body 19 of the locking pin and not only raises said pin but draws or moves it toward the knuckle so as to permit it to clear the lockset seat 28 and drop freely to locked position when the knuckle is fully 100 closed. It may be here mentioned that if while the knuckle 3 is in open position the locking pin 4 should be raised and seated in lockset position upon the ledge 28 of the coupler head a coupling operation can be successfully made, for the tail of the knuckle on its inward rotation will contact with the bevelled surface 9 of the locking pin body and will elevate the locking pin and move it out of alinement with the lockset ledge 28 in the 105 manner heretofore described, thus permitting the locking pin to drop to locked position in front of the knuckle tail. It is evident, therefore, that the coupling operation can be performed with this coupler whether the locking pin 4 is in closed position or is in lockset position, all that is required being that the knuckle shall be open. 110

Projecting forwardly from the front face of the body portion 19 of the locking pin is a 130

lug 13 which comes into contact with the short arm 12 of the knuckle opener when the locking pin 4 performs an extended unlocking movement. The pressure of the lug 13 upon the free end of the short arm of the knuckle opener lever induces the rotation of the knuckle opener and thereby causes its long arm 11 to press upon the rear side of the knuckle tail to force the knuckle open. When the bell-crank knuckle opener lever is in normal position while the knuckle is closed, its long downwardly extending arm 11 rests against the tail of the knuckle, as heretofore described. This position of the knuckle opener places the underside of its short arm 12 approximately at its lowest possible location and leaves a considerable space between the upper surface of the lug 13 upon the lock and the under surface of the short arm of the knuckle opener lever when the locking pin is in lockset position as illustrated in Figure 4. This space or clearance between the lug 13 and the short arm of the knuckle opener lever limits the extent to which the locking pin 4 may move or be jumped upwardly during a closing rotation of the knuckle 3, because when the locking pin, as shown in Figure 5, has been forced over toward the knuckle side of the coupler by the bevelled surface 30 of the head and has come into overlapped relation with the vertical wall 32 of the locking pin chamber, the upper surface of the lug 13 comes into contact with the undersurface of the short arm 12 of the knuckle opener, further upward movement of the locking pin 4 thereby being arrested. This is a very desirable feature of construction, especially in conjunction with the positioning of the vertical surface 32 of the locking pin chamber in laterally spaced overhanging relation to the lockset seat 28 of the coupler head, for by limiting the extent of upward movement of the lock during a coupling operation the interval required for the locking pin to drop in front of the of the knuckle after the latter has reached closed position is reduced, and by arresting lateral movement of the locking pin when its body 19 is forced toward the guard arm side of the head as a result of the lug 13 coming in contact with the short arm 12 of the knuckle opener all possibility of the locking pin catching upon the lockset ledge 28 instead of dropping the full distance to locked position is removed.

It will be noted that while the locking pin is provided with a depending leg permitting it to be actuated from beneath the coupler head, the body portion 19 of the locking pin is of relatively small height. This allows the vertical height of the coupler to be kept within the ordinary requirements and at the same time permits the top of the locking pin chamber to be closed by the top wall of the coupler head. This advantageous shortening of the body portion of the locking pin

and the closure of the upper end of the locking pin chamber is enabled to be accomplished in a coupler in which the lock is automatically elevated by means of the tail of the knuckle by employing a type of lock-to-the-lock means, such as the lug 22, which is effective only when the knuckle is in its closed pulling position.

For receiving the side operating bell-crank lever 29 the lower end of the depending leg 20 of the locking pin is provided at its lower end with a transverse slot 34 which opens rearwardly as indicated at 35. The lock operating lever 29 is pivotally mounted upon the knuckle side of the coupler by means of a pivot pin 36 passing through suitably perforated lugs 37 with which the coupler head is fashioned. The upper arm of the bell-crank lever 29 is formed with an opening 38 for receiving a pull rod or the like (not shown) extending to the side of the car, while the lower end of the lever 29 is flattened and formed at its extremity with a head or enlargement 39 which, when in assembled relation to the locking pin 4, cannot pass through the slot 34 in the lower end of said pin. To limit movement of the locking pin leg toward the knuckle side of the coupler with respect to the bell-crank lifting lever 29 the latter is provided on its forward face with a projection 40 which overlaps and is somewhat spaced from the adjacent side of the depending leg 20 of the lock.

In assembling the coupler the knuckle opener 10 is grasped by the lower end of its long arm and brought parallel to its working position so that the surface of its long arm is close to the top of the throat or opening in the front of the coupler. In this position the body of the long arm of the bell-crank knuckle opener will clear the top edge of the interior wall 16 of the coupler head and the stud or shaft 14 of the knuckle opener may be inserted into the opening or bearing therefor with which the coupler head is provided. The long arm 11 of the knuckle opener may then be rotated toward the knuckle side of the head past the angular face 17 of the wall 16. The knuckle 3 and locking pin 4 can then be assembled with the coupler head in the order found most convenient which is an advantage unusual with side released couplers as it is generally necessary to remove the knuckle from the coupler before it is possible to remove or replace the locking pin. In the present construction the knuckle has a short lateral length of tail and it will be appreciated that when the knuckle is in full or approximately full open position the tail of the knuckle is forward of the opening in the bottom wall of the coupler head through which the locking pin 4 is introduced and that, therefore, the locking pin body can pass through said opening without interference

from the knuckle. It is also to be noted that when in its extreme open position the tail of the knuckle 3 prevents the long arm 11 of the knuckle opener from being brought to the position required for its assembly with the coupler head and that, therefore, the knuckle opener 10 cannot escape or be removed from the coupler while the knuckle is connected to the coupler head by the knuckle pin 2.

In assembling the bell-crank lock-lifting lever 29 with the locking pin the lifter is held in a horizontal position and its lower end is passed through the opening 35 in the slot 34 at the lower end of the depending leg 20 of the locking pin. The lifting lever is then rotated to vertical position and pivotally connected to the lugs 37 of the coupler head by means of the pin 36. When the locking pin 4 and lifter 29 have been thus assembled it is impossible for the locking pin to become displaced to such an extent that the coupler will become inoperative, as the upper portion of the locking pin body 19 is held in place by the guide wall 16 on the interior of the coupler head and movement of the locking pin leg 20 is limited by the lug 40 on the forward surface of the bell-crank lifting lever 29.

An advantageous feature of a coupler constructed in accordance with the invention is that without going between the cars the act of unseating the locking pin from a lockset position can be accomplished by the trainman by simply raising the locking pin by means of the bell-crank lifting lever 29 until the pin assumes the position shown in Figure 5 and thereupon quickly releasing the pull upon the lever 29 so as to permit the lock to drop downwardly to locked position. In railway yard operations it is common practice when distributing the cars to different sections of the yard for the trainman to lockset the locking pin in the coupler at which the parting of the train is to be made. If, however, after this locksetting operation has been accomplished it is discovered that it has been done for a coupler where no parting of the train is desired, it is often necessary to pull the cars apart and re-couple them, since means is seldom provided for restoring the locking pin to locked position and where it is possible to unseat the locking pin from a lockset position it has been heretofore necessary for the trainman to go in between the cars to effect the return of the locking pin to locked position.

I claim:

1. A car coupler having a head, a knuckle pivotally mounted upon the head, and a sliding locking pin for the knuckle movable to locked position under the influence of gravity, said knuckle and locking pin being provided with cooperating means whereby said pin is moved from locked position to an un-

locked position during the closing movement of the knuckle, the coupler head being provided on its interior on the side away from the knuckle with a lockset seat for supporting the locking pin in unlocked position and being provided above and in spaced relation to said seat with a bevelled face which projects laterally beyond said seat toward the knuckle side of the head and also having adjacent said bevelled face and extending upwardly therefrom an interior surface for cooperating with the locking pin to prevent its upper end from shifting into horizontal overlapping relation with said seat after said pin has been elevated to release it from said seat, and said locking pin being formed with a shoulder adapted to engage said lockset seat for supporting said pin in lockset position and being provided with an inclined face for cooperating with said bevelled face of the coupler head to cause the said shoulder to be shifted out of vertical alinement with said seat when the locking pin is elevated to release it from lockset position.

2. A car coupler having a head, a knuckle pivotally mounted upon the head, and a sliding locking pin for the knuckle movable to locked position under the influence of gravity, the coupler head being provided on its interior on the side away from the knuckle with a lockset seat for supporting the locking pin in unlocked position and being provided above and in spaced relation to said seat with a bevelled face which projects laterally beyond said seat toward the knuckle side of the head and also having adjacent said bevelled face and extending upwardly therefrom an interior surface for cooperating with the locking pin to prevent its upper end from shifting laterally into horizontal overlapping relation with said seat after said pin has been elevated to release it from said seat, and said locking pin being formed with a body portion and having a dependent leg extending downwardly from said body portion through the lower wall of the coupler head and being provided with a shoulder adapted to engage said lockset seat for supporting said pin in lockset position and being provided with an inclined face for cooperating with said bevelled face of the coupler head to cause said shoulder to be shifted out of vertical alinement with said seat when the locking pin is elevated from lockset position and being provided on the underside of its body portion with a plurality of inclined surfaces, one of which is adapted to be engaged by the knuckle on its uncoupling rotation to elevate the locking pin for effecting its release from lockset position and the other of said inclined surfaces being adapted to be engaged by the knuckle on a coupling rotation of the latter to raise said lock.

3. A car coupler having a head provided with a locking pin chamber closed at its

upper end, a knuckle pivotally mounted upon the head, a locking pin for the knuckle slidably mounted in said chamber and movable to locked position under the influence of gravity, said knuckle and locking pin being provided with cooperating means whereby said pin is moved from locked position to an unlocked position during the closing movement of the knuckle, and means extending beneath said head for actuating the locking pin to cause it to assume unlocked position, the coupler head being provided on its interior on the side away from the knuckle with a lockset seat for supporting the locking pin in unlocked position and being provided above and in spaced relation to said seat with a bevelled face which projects laterally beyond said seat toward the knuckle side of said head and also having adjacent said bevelled face and extending upwardly therefrom an interior surface for cooperating with the locking pin to prevent its upper end from shifting into a horizontal overlapping relation with said seat after said pin has been elevated to release it from said seat, and said locking pin being formed with a body portion and a dependent leg integrally united to said body portion and extending downwardly therefrom through the coupler head, said body portion being formed with a shoulder adapted to engage said lockset seat for supporting said pin in lockset position and being provided with an inclined face for cooperating with said bevelled face of the coupler head to cause the said shoulder to be shifted out of vertical alignment with said seat when the locking pin is elevated from lockset position, and said dependent leg being provided on its side opposite the knuckle with a laterally projecting lug adapted to extend under a portion of the coupler head when the locking pin is in locked position to prevent said pin from accidentally moving to unlocked position.

4. A car coupler having a head, a knuckle pivotally mounted upon the head, a sliding locking pin for the knuckle movable to locked position under the influence of gravity, and a knuckle opener lever pivotally mounted on the head and adapted to be actuated by the locking pin to effect an uncoupling rotation of the knuckle, said knuckle and locking pin being provided with cooperating means whereby said pin is moved from locked position to an unlocked position during the closing movement of the knuckle, the coupler head being provided on its interior on the side away from the knuckle with a lockset seat for supporting the locking pin in unlocked position and being provided above and in spaced relation to said seat with a bevelled face which projects laterally beyond said seat toward the knuckle side of the head and also having adjacent said bevelled face and extending upwardly therefrom an inter-

rior surface for cooperating with the locking pin to prevent its upper end from shifting into horizontal overlapping relation with said seat after said pin has been elevated to release it from said seat, and said locking pin being formed with a body portion and a dependent leg extending downwardly from said body portion through the coupler head, said body portion being formed with a shoulder adapted to engage said lockset seat for supporting said pin in lockset position and being provided with an inclined face for cooperating with said bevelled face of the coupler head to cause the said shoulder to be shifted out of vertical alignment with said seat when the locking pin is elevated from lockset position and being also provided with a lug for cooperating with one of the arms of said knuckle opener lever, said locking pin being adapted to stand in overlapping relation to said interior surface of the coupler head when said lug comes into engagement with the said arm of the knuckle opener lever when said knuckle is in closed position.

5. A car coupler having a head provided with a locking pin chamber closed at its upper end, a knuckle pivotally mounted upon the head, a locking pin for the knuckle slidably mounted in said chamber and movable to locked position under the influence of gravity, a knuckle opener device pivotally mounted on the head and extending downwardly behind said knuckle, said knuckle and locking pin being provided with cooperating means whereby said pin is moved from locked position to an unlocked position during the closing movement of the knuckle, and a lever pivotally mounted on the side of the coupler head and extending under the latter so as to engage and actuate said locking pin, said locking pin being adapted to engage and actuate said knuckle opener device and being formed with a leg and a relatively short body portion rigidly united to said leg and being provided on the side away from said knuckle with a shoulder for cooperating with said head to prevent accidental unlocking movement of said locking pin, said lever being adapted to cooperate with said leg to cause the body portion of the locking pin to assume unlocked position, said locking pin and coupler head being provided with cooperating means for supporting said pin in lockset position, and said knuckle opener device being adapted to limit the extent of unlocking movement of said locking pin induced by the closing movement of said knuckle.

In testimony whereof I affix my signature
WILLIAM KELSO.
